UNITED STATES PATENT OFFICE.

HENRY CAMPBELL, OF LOGAN, UTAH.

AEROPLANE.

1,308,657.

Specification of Letters Patent. Patented July 1, 1919.

Application filed October 28, 1918. Serial No. 260,000.

To all whom it may concern:

Be it known that I, HENRY CAMPBELL, a citizen of the United States, residing at Logan, in the county of Cache and State of Utah, have invented a new and useful Aero-
5 plane, of which the following is a specifi-
cation.

- The subject of this invention is an aero-
10 plane, and the main objects of the invention
are, first, to provide means, under the con-
trol of the operator, for changing the angle
of incidence of the plane or planes, second,
to provide means for changing the relative
15 positions of the planes, third, to provide
means, readily attached to the usual and
ordinary aeroplane for accomplishing the
foregoing objects, fourth, to generally im-
prove the construction and enhance the util-
ity of aeroplanes.
20 With the foregoing and other objects in
view, which will appear as the description
proceeds, the invention resides in the combi-
nation and arrangement of parts and in the
details of construction hereinafter described
25 and claimed, it being understood that
changes in the precise embodiment of the
invention herein disclosed can be made with-
in the scope of what is claimed without de-
parting from the spirit of the invention.
30 A practical structure for carrying out the
invention is shown in the accompanying
drawings, wherein:—

Figure 1 is a fragmentary view in side
35 elevation of an aeroplane constructed in ac-
cordance with the invention;

Fig. 2 is an enlarged detail view in section
taken on the line 2—2 of Fig. 1;

Fig. 3 is an enlarged detail view in side
40 elevation, part in section, of the operating
lever;

Fig. 4 is a plan view of a fragment of a
material to be used in constructing the
planes;

Fig. 5 is a cross section of the same.

Referring to the drawings by characters
of reference:—

The framework of a usual type of aero-
50 plane is indicated by the numeral 1, and the
aeroplane is provided with wheels 2 upon
which it may run when alighting, or when
starting on a flight. The aviator's cabin is
indicated at 3.

The aeroplane is provided with an upper
55 plane 4, and with a lower plane 5, as herein
shown, though it is not the intention to limit
the invention to biplanes. The planes 4 and

5 are connected and supported by the up-
rights 6, which are arranged on each side of
the frame-work of the aeroplane, and which
are connected on the respective sides by the 60
plates 7, to which they are secured by bolts
6' or otherwise.

The plates 7 are mounted on the protrud-
ing ends of a shaft 8, which extends trans-
versely of the cabin 3, and in the side walls 65
of which it is journaled. The ends of this
shaft 8 are preferably squared so that the
plates 7 may not slip and turn thereon. The
plates 7 are spaced from the sides of the 70
cabin 3 by means of spacing washers 9, and
the plates are provided with arcuate slots 10
through which bolts 11, which are secured
in the sides of the cabin 3, project and serve
to limit the rocking of the plates 7.

For the purpose of rocking the shaft 8 and 75
plates 7 any suitable means may be pro-
vided, that herein shown consisting of a
lever 12 which is secured to and extends ra-
dially of the shaft, the lever being provided
with the usual dog or pawl to engage the 80
teeth of the segmental rack 13.

By rocking the shaft 8 and plates 7, the
angle of inclination of the planes is changed,
and also their positions with respect to each
other. The change in the angle of inclina-
85 tion is indicated by the lines A—A and
B—B, from which it can be seen that the
angle of incidence is changed to make the
machine a high speed, slow climbing plane,
or a slow speed, swift climbing plane, or to 90
set the planes at points between these ex-
tremes.

From the foregoing it will be evident that
the device is adapted to be readily applied to
any of the ordinary aeroplanes now in use so 95
that old machines could easily be recon-
structed in accordance with the invention.
It is also apparent that a machine equipped
with this invention, may readily be changed
from a speed machine to a climbing machine, 100
and that this may be done at any desired
time, even during flight. This change of the
plane still leaves the body of the machine in
its normal, horizontal position, so that its
thrust may still be straight ahead in a hori- 105
zontal line though the machine is climbing
rapidly.

In constructing the planes of the aero-
plane I prefer to use a practically fireproof
material and one that is translucent and not 110
readily seen under the rays of a search-
light.

For this purpose I employ a base 14 of closely woven wire mesh, which may be prepared with silicate of soda, or other suitable filler, and then coated with shellac or other 5 transparent or translucent coating. This gives a strong, rigid plane covering which is not easily ignited, and which will allow most of the rays of light to pass through, thereby rendering the discovery of the plane 10 at night more difficult.

Having described my invention, what I claim as new, is:—

15 The combination with the body of an aeroplane, of upper and lower sustaining planes, uprights connecting the front and rear portions of the upper plane with the corresponding portions of the lower plane, said uprights and planes being rigidly connected, plates connecting the uprights at each side

of the body, a transverse shaft journaled in 20 the body and fixedly connected to the plate, means in the body for rotating the shaft and plate to bodily swing the uprights and planes about the axis of the shaft, means for locking the shaft against rotation, arcuate slots within each plate and means extending from the body and through the slots for limiting the rotation of the plates, uprights, and planes with the shaft, said planes being extended over and under the body, re- 25 spectively.

In testimony that I claim the foregoing as my own I have hereto affixed my signature in the presence of two witnesses.

HENRY CAMPBELL.
